UNITED STATES PATENT OFFICE.

ROBERT E. HURLEY, OF CHICAGO, ILLINOIS.

TRACK-LAYING APPARATUS.

SPECIFICATION forming part of Letters Patent No. 436,087, dated September 9, 1890.

Application filed April 11, 1890. Serial No. 347,522. (No model.)

To all whom it may concern:

Be it known that I, ROBERT E. HURLEY, a citizen of the United States, residing at Chicago, in the county of Cook and State of Illinois, have invented certain new and useful 5 Improvements in Track-Laying Apparatus, of which the following is a specification.

My invention relates to certain improvements in track-laying apparatus of the class 10 wherein the track materials (rails and ties) are carried upon flat cars, from which they are taken by transferring apparatus and delivered in position to be laid upon the track in advance of the construction-train.

15 My present invention has for its object to provide an improved method of and means for delivering the materials in position upon the road-bed; and this method consists in utilizing the moving rails while they are being 20 transferred from the cars to the forward end of the train as carriers for the ties. I have also improved the mechanical construction of the apparatus.

In carrying out my invention I provide a 25 number of cars, on which the materials are placed, the ties being preferably carried on one or more of the forward cars of the train and the rails on the rear cars, the locomotive being connected, preferably, to the rear end of 30 the train and in operation pushing it along as the track-building progresses. I also employ a derrick located, preferably, on the forward cars of the train and having provisions for receiving the ties at the rear of the structure, carrying 35 them bodily over it in a position at right angles to the road-bed, and for delivering them in advance of the forward car, the front end of said derrick projecting beyond the front end of said car. I also provide upon the several cars of the 40 train anti-friction devices—such as rollers—arranged in line on either side of the cars and adapted to receive thereon the rails, which are coupled together and which are forwarded over said anti-friction devices. Friction-rolls 45 are used to seize these rails and forward them along the train, the rolls being driven by suitable gearing and, preferably, from the axle of the cars. On these advancing rails ties are placed and are carried forward by them until 50 the rear end of the derrick structure is reached, whereupon the ties are delivered to cables so placed as to elevate them upon the

derrick, transfer them over it, and deliver them at its forward end in position over the road-bed, the rails meanwhile passing along 55 the derrick structure and being lowered to position by suitable appliances.

In the accompanying drawings, Figure 1^a is a side elevation showing two tie-cars and a portion of a rail-car, and showing also the rear 60 of one of the derrick-cars. Fig. 2^a is a plan view of the same. Fig. 1^b is a side elevation of a part of the derrick structure, the same, together with its accessories, being mounted upon three cars. Fig. 2^b is a plan view of the 65 same. Fig. 1^c is an elevation of the front end of the derrick and showing the rail-lowering appliances. Fig. 2^c is a plan view of the same. Fig. 3 is an end elevation of one of the tie-cars. Fig. 4 is a detail in elevation 70 of parts of a device for adjusting the derrick to variations of curvature in the track. Fig. 5 is a plan view thereof. Fig. 6 is a side elevation of the rail-depositing appliances and showing also the means for carrying the rails 75 from the forward car to the point where they are to be deposited. Fig. 7 is a plan view of the same.

In the drawings, 8 represents tie-cars, and 9 rail-cars. These may be the ordinary flat 80 cars, and will have journaled thereon anti-friction rollers 10, which may have their bearings in the car-body or in a structure removable therefrom. Upon the tie-cars are placed stringers 11, which may be bolted to the car, 85 if desired, and other stringers 12, which are by preference short pieces, may be secured to the fixed stringers by the chains 13. When the movable stringers are placed on top of the fixed ones, the surface of the upper one 90 will be sufficiently above the bearing-face of the rollers as to be above the plane of the upper surface of the rails 14 when passing over said rollers.

15 represents the ties, which when loaded 95 onto the car are placed crosswise on the stringers, as clearly shown in Figs. 1^a, 2^a, and 3.

The rails are loaded on the cars 9 and may be bolted together, making a continuous rail 100 extending from the rail-cars to friction devices located at the rear of the derrick-car. This friction device is shown in Figs. 1^b and 2^b and includes bed-rolls 16, driven by belts

17 from the car-axle. Above these bed-rolls are adjustable friction-rolls 19, which are journaled at the bends of two bell-crank levers 20. One member of said lever is pivoted to the journals of the rolls 16 and the other member carries a weight. A number of rails having been joined together, as before described, may be moved by hand upon the rollers 10 until the ends of the rail-sections are inserted between the rolls 16 and 19, which, being rotated, will draw the rails along. This rail-section will be continuously added to at its rear end and subtracted from at its front end by the removal therefrom of any number of connected rails which can be conveniently handled. Preferably two or three rails are secured permanently together, and then a rail will be only temporarily connected—as, for example, by a single bolt—so as to adapt it to be readily disconnected after passing the friction-rolls. This device admits of keeping the train constantly in motion, and thus avoiding the great loss of time and waste of power necessarily attendant upon stopping and starting a heavy material train for each rail length.

Referring now to the drawings, Figs. 1^b and 1^c, 21, 22, and 23 represent cars, which are used to support a derrick structure. This structure is in the form of a trussed frame supported upon the standards 24. Said standards carry at their upper ends the cross-timber 24^a, and the derrick comprises the horizontal frame-timbers 25, the struts 26, and the tie-rods 27 and 28, which are all connected to and supported by the cross-timber 25^a, which is pivoted between its ends, as indicated at 25^b, and has the anti-friction bearings 25^c resting upon the upper surface of the cross-timber 24^a. This derrick thus pivotally supported may therefore swing laterally sufficient to compensate for curvature in the track. The forward end of this structure projects out beyond the front end of the car a sufficient distance over the road-bed to permit the ties to be carried thereon and deposited upon the road-bed, and the rails to be also carried out and spiked upon the ties as the construction proceeds. The ties and rails are carried forward over the derrick-cars and to their respective places by means of endless belts or cables, the power to drive which is taken from one of the cars.

Referring to Fig. 1^b, 29 represents a driving-belt which is passed around a sprocket-wheel secured on the axle and over a similar sprocket-wheel 30, secured to a shaft bearing thereon a gear-wheel which meshes with a pinion upon a shaft to which is secured a sheave 31. 32 is an endless cable which is passed over the sheave 31, and in order to increase the friction thereon around a similar sheave 33. From this point the cable passes around the sheaves 33^a, 34, and 35, the sheave 34 being supported by a cord 36, passed over a sheave 37 and secured with a weight 38, so as to take up the slack in the cable. From

the sheave 35 the cable passes thence rearwardly and over a sheave 39, secured upon the shaft 18, and thence outwardly to the forward end of the derrick, where it is turned about a sheave 40, and thence returned over a guiding-sheave 41, back over the hub of a sheave 42, and under the hub of an adjoining sheave 43, thence over a guiding-sheave 44, Fig. 2^b, and thence crossing itself at 45 is carried around a sheave 46 from its under side, thence passes out to the forward end of the derrick again, and is returned under a sheave 47 and over a guiding-sheave 48 back to the driving-sheave 31. From the above description it will be seen that a single cable is made by doubling it, as above described, to serve to support and forward ties laid thereon at right angles. Short cables 49, Figs. 1^b and 2^b, are carried over sheaves 50, secured on shaft 18, and these cables are so disposed as to receive the ties from the moving rails at a point in the rear of the rail-moving rolls and elevate said ties to the main forwarding-cable 32. The rails after having been pushed forward by the friction-rolls 16 and 19 and the section separated, leaving two or more rails coupled together, are carried forward and deposited by appliances comprising a frame having rail-carrying tongs moved out and in by a cable driven in either direction at will, bringing said cable into frictional engagement with one or the other of the sheaves 42^a 43^a, which, being rotated in opposite directions, will move said cable either one way or the other. The rails, having been carried out over the points to which they are to be lowered, are engaged by a pair of rail-tongs suspended from a bar or frame, which frame is raised or lowered by means of a cable having a counterbalance-weight at its end, the excess of power required to move it in either direction being applied by hand or in any other convenient way.

Referring now to the drawings, Figs. 1^b, 1^c, 2^b, 2^c, 6, and 7, the rail-carrying frame is shown as composed of a bar or rod 53 and depending links 54, the frame having travelers 55 adapted to move upon a fixed track 56. Connected to the respective ends of the bar 53 is an endless cable 57, which is carried about sheaves 58, Figs. 1^b and 2^b, and thence over sheaves 59 at the forward end of the track. These cables travel in close proximity to the peripheries of the sheaves 42^a 43^a, and beneath these sheaves are pivoted bell-crank levers 60 61, one member of which bears sheaves 62, which are adapted to engage the cable 57 when the bell-crank levers are rocked on their pivots, and thus cause said cable to impinge on the peripheries of the sheaves 42^a or 43^a, as desired. As seen in Fig. 6, the cable is held in contact with the surface of the sheave 43^a, and hence the frame, with the rail-carrying tongs and rail connected therewith, has been moved forwardly to bring the rail to the position shown in Fig. 6, where it has been grasped by the rail-lowering tongs 61, suspended from the frame 62, which is adapted

to be raised or lowered by means of the cable 63, passed under the guide-sheave 64, and thence over the drum 65, its lower end carrying a counterbalance-weight 66. Now, if the 5 rail-carrying tongs be released and the rail-lowering tongs be engaged, the frame 62 may be lowered to deposit the rail-section, as seen in Fig. 1^c, and immediately upon the rail-carrying tongs release the bell-crank lever 61 10 will be operated to bring the cable 57 into contact with the periphery of the sheave 42^a, which will move the cable in the opposite direction and return the frame to the starting-point ready to receive another rail-section. 15 These rail carrying and lowering devices are provided in duplicate, of course, one on each side of the derrick-structure.

In order to compensate for curvature of the track and to maintain the forward end of the 20 derrick over the road-bed, the derrick is pivotally supported and adapted to be turned sufficiently to keep its forward end approximately over the center of the road-bed.

To facilitate the turning of the derrick, I 25 have provided mechanism shown in Figs. 4 and 5 of the drawings, wherein 68 represents links whose upper ends are connected to the side timbers of the derrick at its rear end, and whose lower ends are converged and connected to a common anti-friction roller 69. (Shown by the dotted lines in Fig. 5.) Cables 30 70 and 71 are connected at their inner ends with the lower ends of the links, and the roller thereof has a bearing on the lower side 35 of a cross-timber 72. These cables are made fast, respectively, with shafts 73 74 on opposite sides from their connections to the end of the links, and said shafts are rotatably mounted, bearing on their lower ends a 40 ratchet-and-pawl mechanism 75, and terminating at their upper ends in hand-wheels 76. When either of these shafts is turned, the cable connected thereto will be wound on the 45 shaft, thus drawing the rear end of the derrick toward the shaft which is operated, and the cable paying out from the other shaft, and both shafts being located to secure the derrick in position by the engagement of the 50 pawl with the ratchet. The cables on which the ties are forwarded are so supported on the structure that the rear end of the latter may swing slightly out of line therewith, and the rear end of the derrick need only be 55 swung in ordinary use a very short distance in order to effect the swinging of the front end of the derrick to the extent necessary to maintain it approximately over the road-bed, the derrick being pivoted a distance from its rear end, say, of one-third or one-quarter of 60 its entire length.

In operation it will be understood that the ties will be forwarded and deposited on the road-bed in advance of the rail-laying; but the apparatus is designed to work uninterrupted 65 while the train is continuously in motion.

I do not intend of course to limit my in-

vention to precise details of construction, nor to an apparatus wherein all of the various features of my invention are employed, as it is 70 obvious that the structural features may be changed and that some of the combinations of parts may be used in an apparatus where others are dispensed with.

I claim—

1. The improved method of operating track-laying devices wherein a train of track-material-bearing cars is employed, which consists in connecting the rails together end to end and drawing them forward along the 80 train with the ties superposed thereon, substantially as described.

2. In a track-laying apparatus, the combination of cars for supporting the track materials, said cars having rollers journaled 85 thereon over which the rails are forwarded, and friction-rollers for drawing the rails forward when connected together end to end, the cars being adapted for moving the rails therealong with the ties laid thereon, substantially as described.

3. In a track-laying apparatus, the combination, with cars for supporting the track materials, said cars having journaled on their surfaces two lines of rollers adapted to receive the rails, of supports on the cars bearing beams to sustain the ties above the level of the moving rails, and means for moving the rails with the ties superposed thereon, substantially as described.

4. In a track-laying apparatus, the combination, with cars to carry the ties, provided with rollers thereon to receive and support the rails above the surface of the car-floor, of rail-cars in the rear of said tie-cars, and 105 means for drawing the rails with the ties superposed thereon along the train, substantially as described.

5. In a track-laying apparatus, the combination, with the track-material cars having 110 ways on which the rails may be forwarded when coupled together, and means for supporting the ties above the moving rails, of a derrick structure having endless cables, whereon the said ties are received and whereby 115 they are forwarded over the road-bed in advance of the train, and means for separately forwarding the rails and depositing them in their position upon the ties, substantially as described.

6. The combination, in a track-laying apparatus, of the track-material cars along which the ties and rails are forwarded, the rails coupled together and the ties superposed thereon, substantially as described, a derrick 125 structure having an endless cable to move the ties, an intermediate cable-section to receive the ties from the rails and forward them to the derrick-cable, and friction-rolls for advancing the rails and depositing them in 130 position, substantially as described.

7. In a track-laying apparatus, the combination, with cars whereon the track material is carried and forwarded, substantially as de-

scribed, of a wheel-supported derrick structure having a single cable driven from the car-axles and carried upon friction-rollers journaled at opposite ends of the derrick, and said cable doubled thereon to provide two forwardly-moving loops to receive and forward the ties, and means for forwarding and depositing the rails, substantially as described.

8. In a track-laying apparatus, the combination, with means for supporting and forwarding the track material to a derrick, of a derrick pivotally mounted on a wheel-supported frame, whereby said derrick may be swung laterally to compensate curvature of the track, substantially as described.

9. In a track-laying apparatus, the combination, with means for supporting and forwarding the track materials, of a derrick mounted on a wheel-supported frame having fixed standards and a cross-timber to which the derrick-frame is connected by a king-bolt, and anti-friction rollers between the derrick-frame and said stationary frame, substantially as described.

25 10. In a track-laying apparatus, the combination, with the cars whereon the track materials are forwarded, of a derrick mounted upon cars in front of the material cars and projecting forwardly over the road-bed, of a

frame movable on a way on said derrick and 30 having rail-carrying tongs, and a second frame supported by a cable and having tongs to grasp the rail, said frame being adapted to be lowered to deposit the rail, substantially as described.

35 11. In a track-laying apparatus, the combination, with cars for supporting the track material, said cars having anti-friction rolls whereon the rails may be forwarded when connected together end to end, of friction-40 rolls journaled adjacent to the ways and adapted to rotatably engage the rails whereby to move them along the ways, substantially as described.

12. In a track-laying apparatus, the combination, with cars for supporting the track material, said cars having anti-friction rolls whereon the rails may be forwarded when connected together end to end, of friction-45 rolls journaled adjacent to the ways and driven from the car-axles by suitable gearing and adapted to rotatably engage the rails whereby to forward them along the train, substantially as described.
